Primary Examiner—Gary D. Watson*Attorney, Agent, or Firm*—Nawrocki, Rooney & Sivertson, P.A.**[57] CLAIM**

The ornamental design for a collapsible chair, as shown and described.

DESCRIPTION

FIG. 1 is a perspective view of a collapsible chair showing my new design;

FIG. 2 is a right side elevational view thereof;

FIG. 3 is a top plan view thereof;

FIG. 4 is a bottom plan view thereof;

FIG. 5 is a front elevational view thereof;

FIG. 6 is a rear elevational view thereof; and,

FIG. 7 is a left side elevational view thereof.

The broken lines shown in FIGS. 1, 3, 4, 5 and 6 represent stitching.

FIGS. 2 through 7 have been shown on a reduced scale.
